TRAY

Elmer W. Griese, Jr., 8943 Niles Center Road, Skokie, Ill.

Filed Oct. 21, 1965, Ser. No. 87,692

Term of patent 14 years

(Cl. D44—10)

FIG. 1 is a top plan view of a tray showing my new design.

FIG. 2 is a side view thereof.

FIG. 3 is a vertical section taken along line 3—3 of FIG. 1.

I claim:

The ornamental design for a tray, as shown.
